FIG. 1 is a front elevation view of a telephone set showing my new design as a wall mounted set;

FIG. 2 is a top plan view of the wall mounted set of FIG. 1;

FIG. 3 is a bottom plan view of the wall mounted set of FIG. 1;

FIG. 4 is a right side elevation view of the wall mounted set of FIG. 1;

FIG. 5 is a left side elevation view of the wall mounted set of FIG. 1;

FIG. 6 is an isometric view of the telephone set shown in FIG. 1 and illustrating the new design as a table or desk top set;

FIG. 7 is a front elevation view of a second modified embodiment of a telephone set showing my new design as a wall mounted set;

FIG. 8 is a top plan view of the wall mounted set of FIG. 7;

FIG. 9 is a bottom plan view of the wall mounted set of FIG. 7;

FIG. 10 is a right side elevation view of the wall mounted set of FIG. 7;

FIG. 11 is a left side elevation view of the wall mounted set of FIG. 7;

FIG. 12 is an isometric view of the second modified embodiment of FIG. 7 showing the telephone set as a table or desk top set;

FIG. 13 is a front elevation view of a third modified embodiment of a telephone set showing my new design as a wall mounted set;

FIG. 14 is a top plan view of the wall mounted set of FIG. 13;

FIG. 15 is a bottom plan view of the wall mounted set of FIG. 13;

FIG. 16 is a right side elevation view of the wall mounted set of FIG. 13;

FIG. 17 is a left side elevation view of the wall mounted set of FIG. 13;

FIG. 18 is an isometric view of the third modified embodiment of FIG. 13 showing the telephone set as a table or desk top set;

FIG. 19 is a front elevation view of a fourth modified embodiment of a telephone set showing my new design as a wall mounted set;

FIG. 20 is a top plan view of the wall mounted set of FIG. 19;

FIG. 21 is a bottom plan view of the wall mounted set of FIG. 19;

FIG. 22 is a right side elevation view of the wall mounted set of FIG. 19;

FIG. 23 is a left side elevation view of the wall mounted set of FIG. 19;

FIG. 24 is an isometric view of the fourth modified embodiment of FIG. 19 showing the telephone set as a table or desk top set.

This is a continuation-in-part of design application Serial Nos. D. 378,424, D. 378,425, D. 378,426, D. 378,427, filed July 12, 1973, and now abandoned.

I claim:

The ornamental design for a telephone set, substantially as shown and described.
